UNITED STATES PATENT OFFICE.

NAHUM A. HUSTON, OF AUBURN, MAINE.

DESIGN FOR A COMBINATION TAIL AND GUIDE LIGHT.

54,092.

Specification for Design.

Patented Nov. 4, 1919.

Application filed June 28, 1917. Serial No. 177,588. Term of patent 3½ years.

To all whom it may concern:

Be it known that I, NAHUM A. HUSTON, a citizen of the United States, residing at Auburn, in the county of Androscoggin and State of Maine, have invented a new, original, and ornamental Design for a Combination Tail and Guide Light, of which the following is a specification, reference being had to the accompanying drawing, forming a part thereof.

Figure 1 is a perspective view of the com-

bination tail and guide light, showing my new design, and

Fig. 2 is a side elevation of the same.

I claim:

The ornamental design for a combination tail and guide light, as shown.

NAHUM A. HUSTON.

Witnesses:

FOREST E. LUDDEN,
HENRY W. OAKES.
